Inventor:

W. B. Williams.

UNITED STATES PATENT OFFICE.

WILLIAM B. WILLIAMS, OF WARRENTON, NORTH CAROLINA.

IMPROVEMENT IN PLOWS.

Specification forming part of Letters Patent No. **25,464**, dated September 13, 1859.

To all whom it may concern:

Be it known that I, WM. B. WILLIAMS, of Warrenton, in the county of Warren and State of North Carolina, have invented a new and useful Improvement in Plows; and I do hereby declare that the following is a full, clear, and exact description of the same, reference being had to the annexed drawings, forming part of this specification, in the several figures of which similar characters of reference denote the same part.

Figure 1 is a side view of my improvement. Fig. 2 is a horizontal section on line *x x*. Fig. 3 is a sectional view, showing the attachment of the front piece and the wings to the standard.

The nature of the invention consists in having a piece set in the front of the standard and held in position by two oblique wings attached on either side of the standard for the purpose of preventing wear on the standard.

In the drawings, *B* is the beam; *S*, the standard; *P*, the plate or piece set in the front of standard *S*; *W*, the wings on each side; *C*, the share; *b*, a brace from beam to landside.

The plate *P* is inserted in position on standard, and as its outer surface is beveled and the oblique wings *W* are also beveled in an opposite direction, when they are screwed tight to the standard they clamp the plate *P* and hold it in position. By these means the wear is all on the plate *P*, and not on the standard, and when it becomes worn it is easily replaced by a new one.

The plow is also vertically adjustable by the means of the slotted brace *b* from beam to landside.

I claim—

The combination of standard *S*, plate *P*, and oblique wings *W*, substantially as and for the purpose set forth, with share *C*.

In testimony whereof I have hereunto signed my name before two subscribing witnesses.

W. B. WILLIAMS.
